Inventor:

Patrick J. MacAuley

By Atkins & Atkins,

Attorneys.

UNITED STATES PATENT OFFICE.

PATRICK J. MACAULEY, OF PORTLAND, OREGON.

LIQUID DROPPER.

Application filed April 10, 1923. Serial No. 631,172.

My invention relates to liquid droppers and has for its objects the production of a device by which the separation of the liquid into drops is definitely facilitated; provision is made for liquid discharge from a soft terminal adapted to touch a sensitive organ like the eye, for example, without danger of injuring it; means for regulating the intake capacity of the dropper is provided; and positive protection against accidental breakage of the instrument is incorporated in it.

What constitutes my invention will be hereinafter specified in detail and succinctly set forth in the appended claims.

15 In the accompanying drawing, in which my invention is illustrated in present preferred form of embodiment,

Figure I is a medial longitudinal section of one form of my dropper.

20 Figure II is a similar view of a slight modification of my dropper.

Figure III is an end view of the subject matter of Figure I looking towards the discharge end of the dropper.

25 Figure IV is a section on the line IV—IV of Figure II.

Referring to the numerals on the drawings, 1 indicates a dropper-barrel which is preferably made of rigid material, usually glass, 30 and 2, a collapsible bulb made as of india rubber, and operatively affixed in any suitable manner, usual or preferred, to one end of the barrel 1.

In Figure I the barrel 1 is shown as provided at its end opposite the bulb 2 with a tapered discharge nozzle 3, while in Figure II a barrel 4 is shown as being cylindrical throughout its length. In the former figure a close fitting terminal elastic rubber sheath 5 for the nozzle 3 is shown, while in the latter figure a conical rubber thimble 6 for the cylindrical end of the barrel 4 is shown. The sheath 5 as well as the thimble 6 is provided with a lateral integral annular projection 7 at or near the termination of its skirt portion, which, being made of soft rubber, constitutes at once a cushion and a constricting ring for holding the sheath or thimble in place upon its barrel. The outside diameter 45 of the projection 7 is preferably approximately equal to that of the bulb 2, whereby the members 2 and 7 cooperate to support the intermediate barrel and to protect it against breakage in case it should fall upon 50 a hard surface, as of a table or floor.

The sheath 5 as well as the thimble 6 is

provided with a terminal discharge tip 8, which may be of any length preferred. The special office of the tip is to afford a discharge nozzle of a soft material which may be presented directly to or even in contact with a delicate member, like the eyeball for instance, without danger of injuring it if a patient should give a sudden start during the application of the dropper. The form of barrel 60 1 and its sheath 5 is for some purposes desirable, because, if occasion requires, the sheath may be stripped from its nozzle 3 without impairment of the functional capacity 65 of the instrument. Such provision is useful if it should be desired to use the dropper for a liquid which might injure the rubber of the sheath but which would not affect the glass 70 barrel and nozzle.

Within the barrel 1 or 4, I provide a plug 75 10 which is adjustable endwise of the barrel and is penetrated by a longitudinally disposed duct 11. By the adjustment of the plug 10 as through pressure applied against it from either side by pushing instrument inserted into either open end of the barrel 1, as required, means for measuring the intake 80 capacity of the dropper, to suit the occasion of use, is provided.

What I claim is:

1. In a liquid dropper, the combination 85 with a rigid barrel terminating in a nozzle-like discharge, of a collapsible bulb opposite the discharge end of the barrel, and a plug having a duct within and adjustable endwise 90 of the barrel substantially for the purpose specified.

2. The combination with a liquid dropper 95 having a rigid tubular element, of a slip-over cap of soft elastic material for the dispensing end of said tubular element, said cap being of substantially conical shape and having a dispensing aperture at its apex, the other end of said cap being adjustable over the dispensing end of said tubular element and being 100 provided with an integral radially extending annular flange of substantial width, said flange serving to grip tightly the end of the tubular element to secure the cap in connection therewith and also to maintain said end 105 of the tubular element out of contact with a supporting surface.

3. The combination with a liquid dropper 110 having a rigid tubular element, of a slip-over cap of soft elastic material for the dispensing end of said tubular element, said cap being of substantially conical shape and having a

dispensing aperture at its apex, the other end of said cap being adjustable over the dispensing end of said tubular element and being provided at its extremity with an integral 5 radially extending annular flange of substantial width, said flange serving to grip tightly the end of the tubular element to secure the

cap in connection therewith and also to maintain said end of the tubular element out of contact with a supporting surface. 10

In testimony whereof, I have hereunto set my hand.

PATRICK J. MACAULEY.
